UNITED STATES PATENT OFFICE.

MARTIN W. ZIMMERMAN AND JOHN ZIMMERMAN, OF EARL TOWNSHIP,
LANCASTER COUNTY, PENNSYLVANIA.

IMPROVEMENT IN PUMPS.

Specification forming part of Letters Patent No. 42,617, dated May 3, 1864.

To all whom it may concern:

Be it known that we, MARTIN W. ZIMMERMAN and JOHN ZIMMERMAN, of Earl township, in the county of Lancaster and State of Pennsylvania, have invented a new and simplified Improvement in Operating Ordinary Lifting-Pumps; and we do hereby declare that the following is a full and exact description thereof, reference being had to the accompanying drawings, and to the letters of reference marked thereon.

The nature of our invention consists in simplifying the same by using but one wire instead of two.

Figure 1 illustrates the arrangement of the rocking shafts, arms, and single wire, operated by the crank on the water-wheel at any distance from the pump, and any number of intermediate posts, F, and spring-supports s may be employed. Fig. 2 shows the piston or pump rod x between screw-burs v v on the screw y, held beneath the rocking shaft B for the purpose of regulating the stroke of the piston or pump rod. Fig. 3 illustrates the mode of forming branch posts, if desired.

The drawings clearly show the construction of our invention, and will enable others skilled in the art to make and use the same.

The common water-wheel M, with a crank, N, and connecting-rod, O, attached to the arm J, operates the vibrating motion of the rocker-shaft H, with its perpendicular arm I, to which the wire W is secured. This rocker-shaft is held between two upright posts, G G'. There is also a brace, K, connecting the arms I J. The wire W is supported at intervals in a notch made in the top of a flexible lath or strip, S, of iron, secured to the top of a post, F, any number of which may be employed, accordingly as the distance is more or less great between the pump A and water-wheel M. At any point on the line a rocking shaft, Fig. 3, may be set for the purpose of starting out a diverging line to another pump or adopting a different course in the line of the wire, the arms Q Q' so placed in relation to the vi-

brating upright R, held as shown, as to indicate the desired angle of departure or object aimed at. The rocker-block B, with its arms C C' D, sets over the top of the pump A, held in side supports. Beneath this block is the regulating-screw y, by which the stroke of the pump can be decreased or diminished in proportion as the piston x or pump-rod is brought nearer or is farther removed from the pivot or center of the fulcrum of the vibrating block B, thereby regulating the discharge of water at pleasure or arresting the same entirely. The projecting arm c' may also be employed in like manner as a common pump-handle. To the opposite arm, c, a rod, E, may be attached and employed in stamping or turning a crank, f. To this arm there is ball or weight, L, which aids in the requisite motion, and when but one pump is operated upon a counterpoise, L, is also appended to the arm J, connected with the crank N by the rod O. This latter weight or counterpoise is not needed on J when two pumps are operated, as it can then be applied to the projecting arm c' of such other pump as a counterpoise.

We are aware that the water-wheel and crank are not new, and that they are also employed for operating pumps in connection with two parallel wires, either horizontally or vertically applied to pivoted arms or cross-arms. Such we do not claim. We save the expense of one-half of the wire by using but a single line instead of two, aided by a counterpoise or weighted arm.

What we claim as our invention, and desire to secure by Letters Patent, is—

The use of a single wire in combination with the regulating-screw y, burs v v, rocker-shafts and arms B H R, weights L, operated by a water-wheel and crank, in the manner and for the purpose specified and shown.

MARTIN W. ZIMMERMAN.
JOHN ZIMMERMAN.
